UNITED STATES PATENT OFFICE.

WILLIAM F. A. BUEHNER, OF NEWARK, NEW JERSEY, ASSIGNOR, BY MESNE ASSIGNMENTS, TO REUBEN H. LINDLEY.

DESIGN FOR AN ENGINE-CYLINDER.

49,327.

Specification for Design.

Patented July 11, 1916.

Application filed March 22, 1915. Serial No. 16,292. Term of patent 7 years.

To all whom it may concern:

Be it known that I, WILLIAM F. A. BUEHNER, a subject of Germany, residing at Newark, in the county of Essex and State of New Jersey, have invented a certain new, original, and ornamental Design for Engine-Cylinders, of which the following is a specification, reference being had to the accompanying drawing, forming a part thereof.

Figure 1 is a view in elevation of an engine cylinder showing my new design; Fig. 2 is

a view in elevation taken at right angles to the disclosure in Fig. 1; and Fig. 3 is a view in end elevation.

I claim:

The ornamental design for an engine cylinder, substantially as shown.

In testimony whereof I affix my signature in presence of two witnesses.

WILLIAM F. A. BUEHNER.

Witnesses:

CHAS. HOLZWORTH,
GEORGE STEUHLER.
